FEEDER

Henri J. Burhenne, Rensselaer, N. Y.

Application April 1, 1940, Serial No. 327,110

7 Claims. (Cl. 19—79)

My invention relates to devices for feeding fibrous stock to a processing machine and particularly to a device designed for attachment to the feeding mechanism of a card whereby a more uniform roving of the stock is attained and evener and stronger yarns are produced.

The principal object of my invention is to provide a device of this general character which can be attached to fiber feeding mechanisms of the type now in use whereby the functioning thereof is improved, although it is to be understood that the device is, of course, applicable to new machines especially designed to receive the same.

Broadly, it may be said that my device comprises mechanism which may be interposed or positioned between the stock supplying means and the apron of a card feed whereby a more uniform distribution of the stock is obtained upon the feeding apron or other support from which the stock is carried directly to the card and hence the card is fed at a more uniform rate with the attendant advantages above noted.

In the accompanying drawings which illustrate the application of my invention to a card feeding device, Fig. 1 is a vertical longitudinal section through the machine illustrating, in a diagrammatic way, my improvement therein;

Fig. 2 is a fragmentary diagrammatic side elevation view of the driving mechanism for the feeder; and

Fig. 3 is a fragmentary view similar to Fig. 1 showing a modified type of feeder.

In the drawings, 1 represents the usual hopper into which the stock is fed and carried towards the usual spike apron 2 by means of the apron 3. The apron 2 carries the material upwardly from the hopper past the comb 4, which removes the excess thereof, and around to the stripper roll 5. Here the stock is stripped from the spike apron and dropped into the weighing pan 6. When a predetermined mass of stock has accumulated in the pan 6 it is automatically dropped therefrom by mechanism well known in the art and therefore not illustrated. In the present types of feeders this material is dropped upon the apron 7 which moves in the direction of the arrow 8 to convey the material toward the card.

More specifically, my improvement, as illustrated in Fig. 1, comprises interposing between the weighing pan 6 and the apron 7 a second traveling apron 9 which is positioned to receive the fibrous material dropped from the weighing pan. The material dropped on the apron 9 is condensed by the board 10 which slides in

the slot 11 and is actuated by the reciprocating rod 11'. This is the usual mechanism for condensing the stock on the apron 7 in a Bramwell type of feed. The material thus condensed passes beneath the roll 12 to the stripper 13.

Positioned below this stripper is an oscillating chute 14, one side of which is pivotally connected to the frame of the machine at 15 and the other side of which is pivotally connected at 15'. The sides 16 and 17 of the chute, which may be of wood or metal, are connected together by links 18 which are pivotally connected with the sides 16 and 17 at 19 and 20, respectively. The link 18 is pivotally connected to one end of the reciprocating rod 21 at 22; the other end of the rod 21 being pivotally connected to the wheel 23 at 24 so that as the wheel 23 rotates the chute 14 is oscillated or swung back and forth over the apron 7 from the position 14' to the position 14''. This oscillating motion of the chute is longitudinally of the apron 7, or in the direction of apron movement, rather than transversely of the apron or at right angles to the direction of movement thereof. The chute is, of course, open at the top and bottom but the sides may be closed, if desired, by cloth or other flexible fabric (not shown). The wheel 23 may also operate the presser 25 through the associated bell crank 26 and eccentric rod 27.

In order to avoid complicating Fig. 1 I have not shown therein all of the various belts or chains used for driving the mechanism illustrated. These are shown in a fragmentary, diagrammatic way in Fig. 2. Here, the wheel which operates the eccentric rods 21 and 27 for moving the chute 14 and the presser 25, respectively, is driven by a belt or chain 28 from shaft 29 which may be driven by gearing or other suitable means from shaft 30. The intermediate apron 9 may be driven by a chain or belt 31 from the shaft 32 at one end of the main apron.

In operation, the stock is delivered to the weighing pan 6 by means of the spike apron 2 and the stripper 5, as in the present types of machines. Weighed batches of stock are dropped from the pan 6 to the intermediate apron 9 and removed therefrom by the stripper 13 which drops the stock at a substantially uniform rate into the chute 14.

The speed at which the chute oscillates is preferably so correlated with the speed at which the apron 7 travels and the rate at which the weighed batches of stock are discharged that a continuous sheet or mat of the fibrous material

50

55

comprising a plurality of layers is built up on the support or apron 7 as it is continuously progressed towards the processing machine.

In Fig. 3 I have shown a modified form of my invention in which the intermediate apron 9 shown in Fig. 1 is dispensed with and in which a chute 33 is suspended immediately beneath the stripper 5 and extends downwardly to a point just above the apron 7. The sides 34 and 35 of the chute may be pivotally mounted on the frame of the machine as shown at 36 and 37, respectively, so that it may oscillate about these mountings from the position 33' to 33''. The sides 34 and 35 are pivotally connected by means of a link 38 and this link in turn is pivotally connected at 39 to one end of the rod 40; the other end of the rod 40 being pivotally connected to the wheel 23 at 41. The rotation of the wheel 23 as described in connection with Fig. 1 oscillates the chute in the manner just described.

The apron 7 moves comparatively slowly and the rate at which the chute 23 oscillates in the direction of movement, or longitudinally, of the apron may be correlated with the rate of travel of the apron and with the rate at which the stock is fed to the chute in the manner described above in Fig. 3. However, the weighing pan is not used and hence the stock is fed to the chute 30 continuously and directly from the stripper 5 instead of from a stripper 13 as in the embodiment shown in Fig. 1.

From the foregoing it will be apparent that with my mechanism it is possible to form on the apron or support 7 a continuous fiber mat of substantially uniform thickness throughout which is fed to the processing machine. Thus it is possible to feed stock to the processing machine at a very much more uniform rate than is possible where the stock is dropped directly on the apron 7 from the weighing pan as in the present types of feed.

What I claim is:

1. In a device for forming a continuous mat of fibrous stock of substantially uniform thickness for feeding to a textile processing machine, the combination with a support for said mat during the formation thereof, of a stock distributor positioned over said support, means for supplying stock to said distributor at a substantially uniform rate, means for continuously progressing said mat towards said machine, and means for moving said distributor back and forth in the direction in which said mat is progressed, whereby to effect a substantially uniform distribution of stock over said support.

2. In a device for feeding fibrous material to a textile processing machine, the combination with a movable apron for conveying stock to said

machine, of a chute above said apron for delivering stock directly thereto, and means for moving said chute back and forth over said apron in the direction of movement thereof to effect a substantially uniform distribution of stock thereover.

3. In a device for feeding fibrous material to a textile processing machine, the combination with a movable apron for conveying stock to said machine, of a chute above said apron for delivering stock directly thereto, means for delivering stock to said chute at a substantially uniform rate, and means for moving said chute back and forth over said apron in the direction of movement thereof to effect a substantially uniform distribution of stock thereover.

4. In a device for feeding fibrous stock to a textile processing machine, the combination with a movable apron for conveying the stock to said machine, of oscillating means moving longitudinally of said apron for delivering the stock thereto and spreading it substantially uniformly thereover.

5. In a device for feeding fibrous stock to a textile processing machine, the combination with a movable apron for conveying the stock to said machine, of means for discharging the stock on said apron, and means for reciprocating said discharging means back and forth over said apron in the direction of movement thereof to effect a substantially uniform distribution of stock thereover.

6. A feeding device of the character described comprising a main, movable, feeding apron, a stock weighing device positioned above said apron, a second movable apron positioned between said weighing device and said main apron to receive stock discharged from said weighing device, and a movable distributing device positioned to receive stock from said second apron and distribute it over said main apron.

7. In a device for forming a continuous mat of fibrous stock of substantially uniform thickness for feeding to a textile processing machine, the combination with a support for said mat during the formation thereof, a stock support positioned at a higher elevation than said mat support, means for successively depositing predetermined masses of stock on said stock support, a distributing chute above said mat support, a pivotal mounting for said chute, means for oscillating said chute about said mounting in a direction longitudinally of said mat, a stripper for removing stock from said stock support and delivering it to said chute, and means for progressing said mat during the formation thereof towards said processing machine.

HENRI J. BURHENNE.
